UNITED STATES PATENT OFFICE.

WILLIAM HENRY SIMPSON, OF CHICAGO, ILLINOIS.

SELF-BINDING SHEET-MUSIC COVER.

1,253,435.

Specification of Letters Patent. Patented Jan. 15, 1918.

Application filed September 1, 1916. Serial No. 118,139.

To all whom it may concern:

Be it known that I, WILLIAM HENRY SIMPSON, a citizen of the United States, residing at Chicago, in the county of Cook 5 and the State of Illinois, have invented a new and useful Self-Binding Sheet-Music Cover.

One of the objects of my invention is to provide a binder of simple construction in 10 which a relatively large number of sheet music pieces can be easily and quickly inserted or detached, of which the following is a specification.

I accomplish this object by the binder described herein and illustrated in the accompanying drawings.

Other and further objects of my invention will become readily apparent to persons skilled in the art from a consideration of 20 the following description when taken in conjunction with the drawings, wherein—

Figure 1 is an enlarged transverse sectional view showing a plurality of leaf-engaging strips properly hinged together at 25 each end.

Fig. 2 is a perspective view showing the book-like structure open and the manner of inserting the sheets in the binder.

Fig. 3 is a detail.

30 The same numerals refer to similar parts throughout the views.

In carrying my invention into effect I provide a series of strips of relatively narrow and long stiff material, such as press 35 board, or the like, in length somewhat greater than the length of the sheet of music, and around which the sheet is to be placed in the act of securing it in the temporary loose-leaf binder. I then hinge these 40 strips together, at each end, leaving sufficient space between the hinges within which to contain the sheet of music or the like. After the strips have been thus hinged together, they are suitably connected to covers 45 or backs to provide a book-like structure.

In the drawings, in which one exemplification of my invention is shown, 2 represents a series of parallel, sheet-retaining strips, hinged together at each end by a suitably flexible means, such as tape 1 or the like. The tape is folded around the ends of the strips 2 and glued thereto as by the ap-

plication of a suitable adhesive. The terminals of the intermediate folds are connected together as at 4 to form hinges, and 55 the hinges made stronger by the provision of the fabric backing 3 which may be substantially the same width as the tape 1 in which case the tape may be sewed to the backing 4 between each of the strips 2. 60

When the backing 3 is employed its terminals 5—5 and those of the tape may be glued together and suitably seamed to the cover plates 7—7, respectively. These plates may be composed of book-binders' 65 board; or other suitable material.

The cover plates 7—7 may be connected together by a suitably pliable material, or fabric 10, shown in Fig. 2. This connecting means should be yielding and flexible so as 70 not to interfere with the sheet retaining means to prevent it from opening out flat, as shown. In inserting a leaf, such as 8 and 9, as shown in Fig. 2, the leaf is placed under one of the strips 2, and drawn into 75 position so that a leaf may be on each side of the strip 2 and between the hinges at each end thereof. By this means a folded leaf of music may be placed around each of the strips 2 and the binder may contain as many 80 sheets as there are strips in its composition. The sheets may be easily and quickly removed from the binder.

Having described my invention, what I claim as new and desire to secure by Letters 85 Patent, is—

1. A binder comprising a series of relatively thin, narrow and long parallel strips; a fabric folded around and secured to the ends of the strips to provide hinges at each 90 end, the folds on opposite sides of each strip connected together at like edges and covers for said binder to which the terminals of said fabrics are suitably connected, respectively. 95

2. A binder comprising a series of relatively thin, narrow and long parallel strips; a fabric folded around and secured to the ends of the strips to provide hinges at each end; a flexible backing to which said hinges 100 are also connected and covers for said binder to which the respective terminals of said fabrics and backing are suitably connected.

WILLIAM HENRY SIMPSON.
